PROCESS AND APPARATUS FOR DRYING WET PARTICULATE SOLIDS

Robert R. Goins, Bartlesville, Okla., assignor to Phillips Petroleum Company, a corporation of Delaware
Original application Apr. 9, 1962, Ser. No. 186,038, now Patent No. 3,238,634. Divided and this application Jan. 10, 1966, Ser. No. 519,644

6 Claims. (Cl. 34—10)

This is a division of my application S.N. 186,038, filed Apr. 9, 1962, now Patent No. 3,238,634.

This invention relates to a process and apparatus for drying wet particulate solids. A specific aspect of the invention pertains to a process and apparatus for drying wet pelleted carbon black.

Various powdered materials are wet pelleted into small pellets which must be dried before packaging. Carbon black, catalysts, adsorbents, fertilizers, etc., are some of the materials which must be dried in particulate form before storing or packaging. In drying these solids, rotary drum type dryers are conventionally utilized. The drum is rotated around its horizontal axis while feed is introduced to one end and dried solids are delivered from the other end. This type dryer is heated by means of hot combustion gas formed in a furnace under or adjacent the dryer. One of the problems encountered is the control of the shell temperature of the dryer so that the drying is done efficiently without overheating and/or igniting the material being dried. When utilizing a drum dryer in drying carbon black pellets, it has been found particularly difficult to control the heat input to the dryer so as to properly dry the pellets of carbon black without overheating of the black and the dryer.

It has been proposed to dry pellets in a fluidized bed dryer. This drying technique has been more or less successful but due to the vast heat requirements to vaporize the water from the wet pellets, the dryer must be of large volume capacity in order to allow sufficient heat input. The large capacity dryer requirement means a long residence time of the solids in the dryer which in turn increases the attrition of the solids and the proportion of the solids which pass out with the effluent gas as fines and must be repelleted and recycled to the dryer. This, of course, decreases the efficiency and increases the cost of the drying process.

Accordingly, it is an object of the invention to provide an improved process and apparatus for drying particulate solids. Another object of the invention is to provide a process and an apparatus for drying particulate solids which are highly efficient and effect a minimum of attrition and production of fines in the solids. A further object is to provide a process and arrangement of apparatus for controlling the drying of particulate solids. It is also an object of the invention to provide a process and apparatus for drying particulate solids, such as wet carbon black pellets, which operate more economically than heretofore. Other objects will become apparent to one skilled in the art upon consideration of the accompanying disclosure.

A broad aspect of the invention comprises utilizing hot off-gas from a carbon black or other type reactor as the drying gas for fluidizing and drying wet particulate solids, particularly, carbon black pellets. The solids to be dried are either introduced directly into the off-gas line and transported into a fluidized bed drying zone in the line, or off-gas is taken directly from the off-gas line or smoke header and passed thru a fluidized bed dryer as a fluidizing and drying gas, with effluent gas from the dryer being passed back into the off-gas line. This technique utilizes sensible heat of the off-gas, thereby reducing the heat costs of the process. When this

2

technique is utilized in drying carbon black pellets, the fines from the dryer pass with the off-gas to the bag filter of the carbon black plant thereby simplifying the recovery process.

In the application of the process in which smoke is taken from the reactor off-gas line or smoke header, it is advantageous to utilize fluidized bed dryers arranged in series and to effect most of the drying in the first bed and residual drying in the second bed. In this manner the major portion of the water (all but about 2-50 weight percent) is driven from the pellets or other solids at a relatively low bed temperature with higher bed temperature being utilized in the second dryer. Also, the second dryer is made considerably smaller than the first dryer so as to reduce the residence time of the solids therein and reduce the attrition and proportion of solids converted to fines. The operation of two dryers in series is not limited to the use of smoke or off-gas as the drying gas but, on the contrary, advantages accrue to this technique when utilizing steam, air, CO_2 , and other conventional drying gases.

When drying wet carbon black pellets containing about 43-57 weight percent water (conventional water content of wet pelleted carbon black) fines resulting from abrasion of the pellets run as high as 10 percent or more by weight of the pellets fed to the dryer. These fines must be returned to the pelletizer and recycled thru the dryer as wet pellets which proportionately increases the heat load on the dryer. It has been found that wet carbon black pellets can be dried in two separate beds connected in series with increased efficiency and less fines loss. To illustrate the advantage of utilizing two fluidized beds for drying carbon black pellets having a moisture content of about 50 weight percent, the following example is presented.

Example

Runs were made utilizing a 12" diameter fluidized bed dryer with different air inlet temperatures. Fines in the dryer effluent gas were collected in a cyclone separator. The data obtained are presented in the table below.

TABLE

	Run 1	Run 2
Feed rate, No./hr. wet pellets (50% H_2O)	120	120
Inlet air temperature, F.	1,000	1,200
Bed temp. top F.	172	268
Bed temp. bottom F.	173	275
Dry prod., weight percent moisture	3.5	0.6
Cyclone product, weight percent of dry feed (dry basis)	2.7	6.5
Cyclone product, percent moisture	41.5	3.5

In a similar run utilizing an air inlet temperature of 1400° F., the cyclone product (fines) amounted to a little more than 10 percent of the feed on a dry basis. It should be noted that operating with a lower drying gas temperature and drying to a lower moisture content such as 3.5 weight percent as in Run No. 1 produces only 2.7 percent fines as compared to 6.5% fines when drying to a moisture content of 0.6 weight percent as illustrated in Run 2. By operating with two beds, the first one under conditions of Run No. 1, and then passing the semi-dry black into the second bed operating near conditions of Run 2 it is possible to substantially reduce the fines formed in the process. The second bed is operated at a minimum residence time by reducing the relative size of the dryer. Improvements obtained in this 2-bed operation include (1) efficiency is increased because most of the drying is done at a lower temperature, (2) abrasion of the pellets is minimized, (3) contact time in the second vessel can be controlled (as well as the temperature) to control the amount of after treat-

ing without affecting the efficiency of the drying operation in the primary dryer, and (4) special atmosphere or treating gas can be utilized in the second dryer for after-treating the black while reducing the moisture content to less than about 1 percent by weight.

Another aspect of the invention comprises drying the wet solids in a first fluidized bed, after-treating the dried solids in a second fluidized bed, and cooling the hot solids from the second bed in a third fluidized bed. In this technique cooling gas passed thru the cooling zone as a fluidizing gas is preheated and passed to the treating zone in admixture with other hot gas to provide the optimum temperature for the after-treating step. The hot treating gas is then passed into the drying zone as fluidizing and drying gas. In this process, a great economy of heat is obtained.

Another aspect of the invention comprises controlling the heating conditions in a pair of dryers operated in series by sensing the temperature of the effluent gas from the second dryer and controlling the heat input to the second dryer and simultaneously sensing the variations in the heat input to the second dryer and utilizing the sensed variable to control the heat input to the first dryer. This may be accomplished by different apparatus arrangements as more fully set forth below.

A more complete understanding of the invention may be obtained by consideration of the accompanying schematic drawing of which FIGURE 1 shows an arrangement of apparatus in accordance with one aspect to the invention; FIGURE 2 shows an arrangement of apparatus in accordance with another aspect of the invention; FIGURE 3 shows one arrangement of apparatus and controls for effecting one aspect of the invention; FIGURE 4 shows another arrangement of controls and apparatus for effecting another aspect of the invention; and FIGURE 5 shows apparatus in accordance with a further embodiment of the invention.

Referring to FIGURE 1 a pair of carbon black reactors 10 connect with a common smoke header 12 which feeds into "smoke" line 14 leading to cyclone separator 16. Water line 18 connects with line 14 to supply quench water to the smoke. Line 20 connects cyclone 16 with bag filter 22 which feeds black into line 24 containing pulverizer 26. Off-gas from the bag filter is taken off thru line 28, a portion venting to the atmosphere and another portion being recycled thru line 30 to line 32 leading into blower 34. Carbon black recovered from cyclone 16 and from bag filter 22 is delivered thru lines 24 and 36 to pneumatic conveyor 38 for transport to surge vessel 40. Carbon black from surge vessel 40 passes thru line 42 into wet pelletizers 44 which are supplied with water, which may contain additives such as molasses, from a line 46. All of the apparatus thus far described is conventional in modern carbon black pelleting plants.

Wet pellets containing from about 43 to about 57 percent moisture by weight pass thru line 48 into transport drying line 50 leading into the bottom of fluidized bed dryer 52. Hot smoke for the transport drying line 50 is drawn from "smoke" line 14 by means of lines 51 and 54. Other gas may be introduced thru line 56 as tempering gas to control the temperature and/or to change the character of the drying gas. Air, steam, CO₂, etc., may be introduced at this point.

The term "smoke," as used in the carbon black art and herein, denotes the hot effluent from a carbon black reactor comprising a suspension of finely divided carbon black in combustion gases.

Effluent gas from dryer 52 is passed via line 60 to line 20 or to bag filter 22. Dried pellets from drier 52 are taken off by means of conduit 62 which leads into the lower section of dryer 64. Fluidizing and drying gas for dryer 64 may also be smoke or off-gas obtained from line 54 thru lines 66 and 68. Here again, additional drying gas of a different character may be introduced thru line 70.

Effluent gas from dryer 64 is passed via line 72 to fines-separating cyclone 74 or it may be passed via line 76 to line 20 for passage to bag filter 22 to separate fines therefrom. In the event the fines are recovered in cyclone 74, they are passed thru line 78 to pneumatic conveyor 38 for recycle to the pelletizers.

In the event only one fluidized bed dryer is utilized to accomplish the drying step, dried pellets in line 62 are passed via line 80 directly to bagging or storage. When both dryers are utilized, effluent dry pellets are passed via line 82 to line 80 for passage to bagging or storage.

The degree of completion of the drying process in dryer 52, when dryer 64 is not used, is controlled by manipulation of the flow rate of drying gas to the process by operation of valves 84 and 86 and by sensing the temperature of the effluent drying gas in line 60 feeding this signal from transmitter 88 to temperature recorder controller 90 which positions motor valve 92 in water line 94, thereby manipulating the amount of quench water added to the effluent smoke and, indirectly, the off-gas temperature in line 60 from dryer 52.

Referring to FIGURE 2, a fluidized dryer 100 is provided with a wet pellet inlet line 102, inlet drying gas line 104, and an effluent gas line 106. Dried pellets are taken off thru line 108 and passed to the lower section of fluidized treater 110. Fluidizing gas for treater 110 is supplied thru line 112 and effluent gas is passed thru line 114 to line 104 as drying gas to dryer 100. Combustion gas is added thru line 116 as needed to supplement the drying gas from line 114 in sufficient volume to provide a fluidizing flow rate and at sufficient temperature to provide the desired drying gas temperature in dryer 100. Effluent treated pellets from treater 110 are passed thru line 118 to cooler 120 for cooling to a temperature satisfactory for bagging or storing of the pellets.

Air or other gas for cooling the treated pellets is introduced to cooler 120 thru line 122. Off-gas from dryer 100 may be passed thru line 124 into line 122 to supplement the cooling gas when desired. This off-gas may also be recycled to effluent line 126 from cooler 120 thru line 128. All or any part of the gas in line 126 may be passed to line 112 as treating gas thru line 130. A substantial portion of the treating gas in line 112 is supplied from line 132, preferably as combustion gas or superheated steam. Cooled pellets are withdrawn from cooler 120 thru line 134.

Fluidizing vessels and the depth of the fluid beds therein are sized to give proper hold up time and to provide as well as to require compatible volumes of gases as needed in the different steps. Such beds are relatively deep and only a few feet in diameter. Integrated gas temperature and volume controls are used to maintain proper conditions in the beds. Volume controls are needed to produce the necessary fluidization velocities in the beds. Temperatures within the beds are principally controlled by manipulation of the inlet temperatures of the gases to each of the beds. Desired compositions of the gases used in the drying and treating beds can be achieved by recycle of off-gas from the dryer to the cooling bed. To further reduce oxygen (if desired) the air used in the cooling bed can be used as combustion air for the treater and dryer. Cyclones may be required on the gas effluent from each of the beds to remove small amounts of fines.

Drying in the arrangements shown in FIGURE 1 can be accomplished in the first fluidized bed at bed temperatures in the range of about 275 to 300° F. with short residence time; and drying to around 3.5 percent moisture can be effected at about 175° F. as shown in the illustrative example above. Drying is done in the first fluidized bed preferably in the temperature range of 150 to 300° F. Pellets are then passed to the second drying and/or treating bed where temperature is raised to the range of about 500 to 1200° F. to complete the drying and to control the properties of the black. Carbon black

pellets then pass to the cooling bed (FIG. 2) for cooling to the range of about 200 to 500° F. and, preferably, below 400° F. for bagging or storage.

Referring to FIGURE 3, a rotary dryer 140 is provided with a wet pellet inlet line 142 and a dried pellet effluent line 144. Burners or burner means 146 below the dryer drum are supplied air and fuel gas from line 148. These burners or burner means may be radiant burners located either outside or inside of the dryer shell. Off-gas is vented through stack 150 or any portion thereof may be passed via line 151 to line 169 to supplement the drying gas in line 160. A second dryer in the form of a fluidized bed dryer 152 is connected with line 144 to receive partially dried pellets. Hot drying and fluidizing gas is supplied by burning an air-fuel mixture in furnace 154, supplied through fuel line 156 and air line 158. The hot combustion gas is introduced to the bottom of dryer 152 via line 160. Off-gas from dryer 152 passes through line 162 to the filter of the carbon black plant.

In the operation of the dryers of FIGURE 3, the temperature of the effluent gas in line 162 is sensed and a signal is emitted by transmitter 164 to temperature-recorder-controller 166 which manipulates motor valve 168 in response to the signal received so as to add more fuel upon sensing a lower temperature and cut down on the rate of fuel flow when a higher temperature is sensed than a predetermined operating temperature. In this arrangement the flow of air in line 58 is maintained substantially constant by means of motor valve 170, controller 171, and flow transmitter 172. In order to proportion the drying load between the two dryers (140 and 152), the flow rate of fuel in line 148 is also manipulated by means of temperature-recorder-controller 174 which is in control of motor valve 176 and receives a measurement signal from transmitter 178 in response to the sensed temperature of the gas in line 160. In order to protect the equipment, temperature transmitter 175 senses the shell temperature of the rotary dryer and acts through controller 174 to limit fuel gas flow through line 148 via valve 176 to prevent exceeding the maximum set temperature for the safe operation of the dryer.

To illustrate the operation of the control system of FIGURE 3, when the drying load on the system (dryer 140 and dryer 152) changes (for example, increases) by an increase in the feed rate of wet pellets or by an increase in the initial water content of the pellets, this effect passes to dryer 152 by virtue of a higher water content of the pellets in line 144 which subsequently causes the temperature of the off-gas in line 162 to decrease, since more water enters the dryer via the pellets but the rate of heat input via line 160 has not yet been increased.

This change in temperature in line 162 is sensed and the control system changes the heat input to both dryers. In response to this off-gas (line 162) temperature decrease, controller 166 increases the opening of valve 168, thus increasing the fuel gas flow rate, which raises the combusted gas temperature and thereby increases the heat input to dryer 152 via line 160. This increased heat input dries the pellets discharged by line 153 to a greater degree, thereby increasing the temperature of the off-gas in line 162 toward its desired value (set point to controller 166). The increase in combusted gas temperature in line 160 over its previous value (which was equal to TRC 174 set point), indicating that an increase in drying load had taken place, is then used by TRC 174 (in cooperation with its set point) to increase the fuel gas flow rate to rotary drier 140 so as to transfer at least a portion of this increased drying load from the fluid bed dryer to the rotary dryer. This system is doubly advantageous in that (1) it brings about "load sharing" of two serially operated units performing the same general function and (2) the rapid changes in drying load are compensated for in the unit which can be manipulated more rapidly, and the slower-occurring drying load changes, 75

which persist for some period of time, are first corrected by the fluid bed dryer, with the increased load being transferred (gradually during a period of time) to the greater drying capacity unit (rotary drier) thus leaving the faster correcting fluid bed unit "in the middle of its drying capacity range" ready to compensate for the next drying load transient condition.

When the heat load on dryer 140 decreases because of lower feed rate of wet pellets or lower water content, the opposite adjustment is made in valves 168 and 176 by the control system. In the arrangement shown in FIGURE 3, dryer 140 may also be a fluidized bed dryer (as illustrated in FIGURE 4) with a different set of controls.

Referring to FIGURE 4, a first dryer 180, which may be either a rotary or a fluidized bed dryer, is supplied wet pellets through line 182 and heat for drying through line 184 from furnace 186. Air at a constant rate is fed to furnace 186 via line 188 and fuel gas via line 190 under the control of motor valve 192. Effluent drying gas is vented through line 194 or passed to the filter, and effluent semi-dry pellets are passed via line 196 to second fluidized bed dryer 198. Fluidizing and heating gas is passed into the bottom of dryer 198 through line 200 which connects with furnace 202. This furnace is supplied an air-fuel mixture through line 204 under the control of motor valve 206. Effluent dry pellets are recovered through line 208 and effluent drying gas from the second dryer passes to the filter via line 210.

The control system for operation of the dryer of FIGURE 4 comprises a temperature transmitter 212 responsive to the temperature in line 210 and emitting a signal proportional to the sensed temperature to TRC 214. Instrument 214 controls valve 206 in response to the sensed temperature so as to increase the flow rate of combustible mixture to furnace 202 when the sensed temperature is below the desired (set point) temperature of the gas in line 210 or to decrease the flow rate to furnace 202 when the sensed temperature is above normal operating temperature. The heat input to dryer 180 is simultaneously controlled by an arrangement of instruments comprising flow transmitter 216 and flow recorder controller 218 which is in control of motor valve 192 so that upon an increase in flow rate in line 204, the flow rate of fuel in line 190 is also increased to proportion the heat loads on the two dryers. The opposite adjustment is made when the temperature in line 210 is too high, indicating above-normal heat input to the dryers for the drying load imposed thereon.

To prevent the first dryer's temperature from becoming excessive, as heretofore mentioned, each pair of transmitters 175-178 and 216 and 217 in FIGURES 3 and 4 may operate through a low pressure selective relay included within TRC 174 and FRC 218, to select the lower signal (temp.) and pass it to its respective controller. Taylor Instrument Co., Model SK 11359 is an illustration of this type of instrument.

An alternative control system on the first dryer of FIGURE 4 is illustrated by line 220 which connects TRC 214 directly with motor valves 192 and 206 (eliminating transmitter 216 and controller 218) so that the signal from TRC 214 simultaneously either increases or decreases the flow through the lines which these valves control to change the heat requirements of the process and simultaneously proportion the loads on the two dryers.

FIGURE 5 shows a fluidized bed dryer 230 positioned directly in "smoke" line 232 directly downstream of one or more carbon black reactors 234. Wet pellets are fed into the lower section of dryer 230 through line 236 and dry pellets are withdrawn through line 238 from the top of the fluidized bed 240. It is also feasible to introduce the pellets through line 242 directly into "smoke" line 232 sufficiently upstream of dryer 230 to provide substantial transport drying of the pellets prior to their introduction to dryer 230.

Temperature control of the "smoke" to dryer 230 is effected by sensing the effluent gas temperature by conventional means and transmitting the sensed temperature by means of transmitter 244 to controller 245 which operates motor valve 246 in water quench line 248. In 5 this manner the effluent temperature from the dryer is regulated by regulating the amount of quench water introduced to the "smoke" stream.

When utilizing "smoke" from a carbon black reactor as drying and fluidizing gas, the temperature of the smoke is usually controlled (by water quench) in the range of 500 to 1500° F. and preferably 800 to 1500° F., but temperatures up to reactor outlet temperature may be used. The gases from the dryer which contain fines from the pellets, as well as most of the original loose black 15 from the "smoke," pass through the "smoke" line to the plant filters and thus eliminate the need for a separate filter for the dryer off-gas.

Advantages of the use of "smoke" as the drying gas include (1) elimination of need for fuel gas and equipment for burning same to produce hot gas, (2) smoke is completely inert (no free O₂), (3) no extra filter and no extra load on regular filters of the plant, and (4) the dryer acts as an elutriator to remove fines so that product has less dust than product from a rotary dryer. 20

It is feasible to utilize "smoke" line 232 as a transport dryer to effect substantially the entire drying process and utilize vessel 230 as a cyclone separator to remove the dried pellets. In fact, drying of any wet particulate solids may be effected wholly by transport drying followed by separation of the dried particles from the hot 25 transport gas in a cyclone separator, bag filter, or other suitable separation means.

In the drying of particulate coal (being transported in a slurry) before feeding same to a furnace, stack gas from the furnace can be utilized effectively as the drying gas in accordance with this invention. Transport drying is effective in this application.

Certain modifications of the invention will become apparent to those skilled in the art and the illustrative details disclosed are not to be construed as imposing unnecessary limitations on the invention.

I claim:

1. A process for drying wet pellets compacted from carbon black which comprises the steps of:

- (1) entraining said pellets in a stream of hot drying gas comprising essentially smoke from the carbon black reactor wherein the carbon black was produced, water-quenched to a temperature in the range of 500 to 1000° F. to form a suspension of said 50 pellets in said gas;
- (2) passing the suspension of step (1) through an elongated transport drying zone of substantial length to dry same substantially;
- (3) passing said pellets from the zone of step (2) upwardly into a fluidized bed dryer of expanded lateral dimension relative to the zone of step (2), said gas being the fluidizing gas;
- (4) maintaining said pellets in fluidized condition in the dryer of step (3) so as to further dry said pellets to a relatively low moisture content; and
- (5) separately withdrawing gas and dried pellets from the dryer of step (3).

2. The process of claim 1 wherein a selected withdrawn gas temperature from step (5) to effect drying to a moisture content of not more than 3.5 weight percent is maintained by controlling the flow rate of said drying gas and by sensing the temperature of said withdrawn gas, injecting aqueous quenching fluid into said smoke as it flows directly from said reactor, and controlling the flow rate of said quenching fluid in response to the sensed temperature to maintain said selected withdrawn gas temperature.

3. Apparatus for forming and drying wet carbon black pellets comprising in combination

- (a) a carbon black reactor having an effluent hot smoke line;
- (b) an upright fluidized bed dryer having an unobstructed drying zone, an inlet in its lower section, a gas outlet in its upper section, and a pellet outlet from an intermediate section;
- (c) an elongated transport and dryer conduit of substantial length connected at its downstream end to the inlet of (b) for substantially drying said pellets therein;
- (d) pellet inlet means connected to the upstream end of the conduit of (c); and
- (e) a line connecting the smoke line of (a) with the upstream end of the conduit of (c) for supplying smoke as a drying, transport, and fluidizing gas to said conduit.

4. The apparatus of claim 3 including a pellet cooler connected by conduit means with the pellet outlet of (b).

5. The apparatus of claim 3 including carbon black recovery means connected with the gas outlet of (b), a wet pelletizer connected by conduit with said recovery means, and a transport line for wet pellets connecting said pelletizer with an upstream section of the conduit of (c).

6. The apparatus of claim 5 including

- (f) a quench line connected with the hot smoke line of (a) having a motor valve therein;
- (g) means for sensing the temperature of the gas from the gas outlet of (b) and emitting a signal proportional to the sensed temperature;
- (h) and a temperature controller connected to receive the emitted signal of (g) and operate the motor valve of (f) to control said outlet gas temperature.
